UNITED STATES PATENT OFFICE.

EUGENE RILEY EDSON AND BENJAMIN F. SILLIMAN, OF CLEVELAND, OHIO, ASSIGNORS TO THE EDSON REDUCTION MACHINERY COMPANY, OF AUGUSTA, MAINE, A CORPORATION OF MAINE.

DRIER.

SPECIFICATION forming part of Letters Patent No. 744,179, dated November 17, 1903.

Application filed April 17, 1903, Serial No. 153,065. (No model.)

To all whom it may concern:

Be it known that we, EUGENE RILEY EDSON and BENJAMIN F. SILLIMAN, citizens of the United States of America, residing at Cleveland, in the county of Cuyahoga and State of Ohio, have invented certain new and useful Improvements in Driers; and we do hereby declare the following to be a full, clear, and exact description of the invention, such as will enable others skilled in the art to which it pertains to make and use the same.

This invention relates to improvements in driers, and pertains more especially to a drier comprising a sectional jacketed interiorly-chambered horizontally-arranged cylinder which forms the drying-chamber of the drier and is closed at its ends by suitably-applied heads.

One object of this invention is to render the drier long-lived by the formation of the drying-chamber by several separable and circumferentially-adjustable cast-iron annular cylinder-sections assembled endwise between the heads of the drier and forming the surrounding wall of the said chamber, with the said wall hollow or interiorly and circumferentially chambered to form a heating-jacket.

Another object is to form in the construction of each annular cylinder-section an annular cast-iron outer or jacket-forming shell, which is formed integral with the inner annular cast-iron shell which the said cylinder-section comprises, with each cylinder-section provided at each end and externally with a laterally and outwardly projecting annular flange, with adjacent flanges of adjacent cylinder-sections separably secured together, with the outer shell of each cylinder-section enough larger diametrically than the inner shell of the said cylinder-section to form between the said shells an annular heating-fluid-receiving chamber *n*, which extends circumferentially of the said cylinder-section, and with communication between the annular heating-fluid-receiving chambers of adjacent cylinder-sections suitably established.

Another object of this invention is to render the construction simple and convenient in the assemblage and renewal of parts.

With these objects in view and to the end of realizing other advantages hereinafter appearing this invention consists in certain features of construction and combinations of parts hereinafter described, and pointed out in the claims.

In the accompanying drawings, Figure 1 is a side elevation, largely in central section, of a drier embodying the invention which constitutes the subject-matter of this application. Fig. 2 is a transverse vertical section on line 2 2, Fig. 1, looking in the direction indicated by the arrow. Fig. 3 is a section on the curved line 3 3, Fig. 2, looking in the direction indicated by the arrow.

Our improved drier comprises an interiorly-chambered jacketed cylinder composed of annular sections *a*, assembled endwise and horizontally arranged in line between two heads *b*, which close opposite ends, respectively, of the drying-chamber formed by and interiorly of the said cylinder. The cylinder of the drier illustrated is therefore arranged horizontally and comprises five annular sections *a*. Each cylinder-section *a* comprises an inner cylindrical cast-iron shell *c*, surrounded by a jacket-forming outer cylindrical cast-iron shell *f*. The outer shell *f* of each cylindrical section *a* is enough longer diametrically than the inner shell *c* of the said section to form between the said shells an annular heating-fluid-receiving chamber *n*, which extends circumferentially of the said cylinder-section. Each cylinder-section *a* is provided at each end and externally with a laterally and outwardly projecting annular flange *d*. Each cylinder-section is provided interiorly of its chamber *n* and centrally between the ends of the said section with radially-arranged webs *e*, which tie together and brace apart the shells *c* and *f* of the said section and strengthen the latter.

The chamber *n* of each cylinder-section *a* has end walls *g*, which extend circumferentially of the said section, which walls *g* are slotted or perforated laterally, as at *r*, to form ports arranged at suitable intervals circumferentially of the said cylinder-section. Communication between the chambers *n* of ad-

adjacent cylinder-sections *a* is established by the ports *r* of the adjacent end walls *g* of the said sections, and the said ports are arranged, preferably, next to the inner sides of the outer shells *f* of the said cylinder-sections.

The central and two end cylinder-sections *a* correspond in dimensions and construction in every respect, and the two remaining and intermediate cylinder-sections *a* correspond in dimensions and construction in every respect. All the cylinder-sections correspond in construction so far as the assemblage of the parts is concerned, and the said sections are therefore interchangeable.

15 Adjacent sections *a* are separably secured together by suitably-applied bolts and nuts. Adjacent flanges *d* of adjacent cylinder-sections *a* have registering horizontally-arranged holes *s*, extending laterally therethrough at 20 suitable intervals circumferentially of the said cylinder-sections and engaged by bolts *t*, and correspondingly-threaded nuts *u* are mounted upon the screw-threaded shanks of the said bolts, and the arrangement of the 25 parts is such that the said cylinder-sections *a* have their said flanges clamped together by and between each bolt *t* and the nut *u* upon the said bolt. It will be observed, therefore, that adjacent cylinder-sections *a* are 30 separably clamped together.

Each intermediate cylinder-section *a*, interposed between the central section *a* and an end section *a*, is provided with two pipe connections *w* and *W*, arranged diametrically opposite and at the top and bottom, respectively, of the drier, which pipe connections extend through the chamber *n* of the said intermediate section and have their interior passage-ways communicating with the 40 main or drying chamber of the drier.

By the construction hereinbefore described it will be observed that upon loosening the nuts *u*, instrumental in clamping adjacent cylinder-sections *a* together, each of the said 45 sections is rendered free to be turned independently of the other of said sections, and hence the cylinder-sections are adjustable circumferentially.

In the drier, as illustrated in Fig. 1, the 50 pipe connections *W* form the material-discharging outlets of the drying-chamber of the drier, through which outlets material is removed from within the said chamber, whereas the pipe connections *w* form charging-apertures and vapor-outlets, through which the said chamber is supplied with material to be dried or heated within the said chamber and which accommodate the escape of vapors and gases from the said chamber.

55 The heads *b*, which close the ends of the drying-chamber of the drier, are preferably interchangeable. Each head *b* overlaps the adjacent flange *d* of the adjacent end cylinder-section *a*, and suitably-applied bolts and 60 nuts clamp the said head to the said flange, as at *B*. The heads *b* are provided centrally

with stuffing-boxes *G*, which surround the suitably-supported stirring-shaft *K*, which is arranged horizontally and extends centrally through the drier. The shaft *K* is provided within the drying-chamber with radially-arranged stirring-arms *L*. Preferably each head *b* is provided at its outer side with a bracket *x*, which affords bearing to the shaft *K*. The shaft *K* is provided at one end with a driving-wheel *y*, to which power is applied in any approved manner. Each head *b* is provided with two diametrically opposite ports *H* and *D*, arranged near the top and bottom, respectively, of the said head and 70 communicating with ports *r*, formed in the adjacent end wall *g* of the chamber *n* of the adjacent end cylinder-section *a*. It will be observed also that the ports *H* form the steam-inlets of the jacket of the drier, whereas the 75 ports *D* constitute the drain passage-ways of the said jacket.

The upper portions of the shells *c* of the cylinder-sections *a*, because of their greater exposure to iron-corroding vapors and gases 80 arising from material treated within the drying-chamber, become worn more rapidly than the lower portions of the said shells, and consequently the importance of the circumferential adjustability of the cylinder-sections 85 *a* is obvious. When, therefore, the upper portions of the shells *c* of the cylinder-sections *a* become worn to such an extent that a readjustment of the said sections is deemed advisable, the nuts *u* are loosened to accommodate the said readjustment, whereupon the cylinder-sections *a* are turned half-way round, and then the pipe connections *W* will be the charging-apertures or vapor-outlets of the drier, the pipe connections *w* will form 90 material-discharge passage-ways, the ports *H* will be drain passage-ways, and the ports *D* will form steam-inlets. Of course the nuts *u* are retightened upon a readjustment of the cylinder-sections *a*. By the construction 95 hereinbefore described it is obvious also that any two cylinder-sections showing a great difference in the wear of their shells *c* may be interchanged to advantage.

The slots or ports *r* in each of the adjacent 100 end walls *g* of adjacent cylinder-sections *a* register with the slots or ports *r* in the other of the said walls. The arrangement of the said ports *r* of each end wall *g* of each chamber *n* circumferentially of the drier is such 105 that the chambers *n* of the end cylinder-sections *a* are in either adjustment of the said sections and heads *b* in communication with the ports *H* and *D* of the said heads and communication between the chambers *n* of adjacent cylinder-sections is in either adjustment 110 of the said sections established at and centrally of the bottom of the said chambers, so that any water resulting from condensation 115 of steam within the said chambers can freely 120 pass between the said chambers.

The arrangement of the bolt-holes *s* of ad-

jacent flanges *d* of adjacent cylinder-sections *a* is such that the holes *s* in each of the said flanges shall register with the holes *s* in the other of the said flanges in either adjustment of the said cylinder-sections.

- Each head *b* is shown provided in Fig. 1 with two pipes *P* and *Q*, which communicate with the ports *H* and *D*, respectively, of the said head and are each provided with a normally closed valve *R*. In the position of the heads illustrated the pipes *P* are employed to conduct steam through the ports *H* and the connected ports *r* in the end cylinder-sections into the heating-fluid-receiving chambers *n* of the said cylinder-sections, and the pipes *Q* are employed as drain-pipes to drain from the said chambers *n* through the ports *D* and the connected ports *r* of the said cylinder-sections any water accumulating within the said chambers *n*; but obviously when the said heads *b* are circumferentially adjusted or turned half-way round the pipes *Q* will then be used as steam-pipes and the pipes *P* will then be used as drain-pipes.
- The drier illustrated is shown resting upon two standards *J*, arranged below opposite ends, respectively, of the drier, and the drier is removably secured to the said standards by some of the same bolts and nuts employed in securing the heads *b* to the end cylinder-sections.

What we claim is—

1. A drier comprising two heads arranged a suitable distance apart laterally of each other and closing opposite ends respectively of the drying-chamber, and a sectional cylinder consisting of several separable and circumferentially-adjustable annular sections assembled endwise between the aforesaid heads and forming the surrounding wall of the aforesaid chamber and each cylinder-section having an annular cast-iron inner shell and an annular cast-iron outer or jacket-forming shell integral with and surrounding the inner shell and enough larger diametrically than the said inner shell to form between the said shells an annular heating-fluid-receiving chamber which extends circumferentially of the said cylinder-section and has ported end walls, with the ports of adjacent end walls of the heating-fluid-receiving chambers of adjacent cylinder-sections arranged to establish communication between the said chambers, and the cylinder-sections being provided, at the ends and externally, with laterally and outwardly projecting annular flanges, with adjacent flanges of adjacent cylinder-sections separately secured together.
2. A drier comprising two heads arranged a suitable distance apart laterally of each other and closing opposite ends respectively of the drying-chamber, and a sectional cylinder consisting of several separable and circumferentially-adjustable annular sections assembled

endwise between the aforesaid heads and forming the surrounding wall of the aforesaid chamber, and each cylinder-section having an inner shell and an outer or jacket-forming shell surrounding the inner shell and enough larger than the said inner shell to form between the said shells a heating-fluid-receiving chamber which extends circumferentially of the said cylinder-section and has ported end walls, with the ports of adjacent end walls of the heating-fluid-receiving chambers of adjacent cylinder-sections arranged to establish communication between the said chambers.

3. A drier, comprising two heads arranged a suitable distance apart and closing opposite ends respectively of the drying-chamber, and a sectional cylinder comprising several separable annular sections assembled endwise between the aforesaid heads and forming the surrounding wall of the aforesaid chamber, and each cylinder-section having an inner shell and an outer or jacket-forming shell surrounding the inner shell and enough larger than the inner shell to form, between the said shells, a heating-fluid-receiving chamber which extends circumferentially of the said cylinder-section, and adjacent heating-fluid-receiving chambers having adjacent end walls provided with ports arranged to establish communication between the said chambers.

4. A drier comprising two heads arranged a suitable distance apart laterally of each other and closing opposite ends respectively of the drying-chamber; a sectional cylinder consisting of several separable and circumferentially-adjustable sections assembled endwise between the aforesaid heads and forming the surrounding wall of the aforesaid chamber, with the said wall hollow or chambered interiorly and circumferentially to form a heating-jacket; means whereby fluid is conductible into the jacket-chamber through the aforesaid heads, and means whereby the jacket-chamber is drainable through the said heads.

5. A drier comprising two heads arranged a suitable distance apart laterally of each other and closing opposite ends respectively of the drying-chamber; a sectional cylinder consisting of several interchangeable and circumferentially-adjustable annular sections assembled endwise between the aforesaid heads and forming the surrounding wall of the aforesaid chamber and each cylinder-section having an inner shell and an outer or jacket-forming shell surrounding the inner shell and enough larger than the inner shell to form between the said shells a heating-fluid-receiving chamber extending circumferentially of the said cylinder-section; means for supplying the heating-fluid-receiving chambers of the cylinder-sections with a heating fluid; means for draining the said chambers;

a stirring-shaft extending centrally and longitudinally of and through the cylinder and through the aforesaid heads; brackets secured to the heads and supporting the shaft, and 5 one of the cylinder-sections being provided with two pipe connections communicating with the drying-chamber and arranged at the top and bottom respectively of the drier.

Signed by us at Cleveland, Ohio, this 6th day of April, 1903.
